UNITED STATES PATENT OFFICE.

EBENEZER REGINALD MORRIS, OF SYDNEY, NEW SOUTH WALES, AUSTRALIA.

RIFLE-PERISCOPE.

1,264,133.

Specification of Letters Patent. Patented Apr. 23, 1918.

Application filed July 17, 1916. Serial No. 109,745.

To all whom it may concern:

Be it known that I, EBENEZER REGINALD MORRIS, a subject of the King of Great Britain, residing at Sydney, in the State of New 5 South Wales, Commonwealth of Australia, have invented certain new and useful Improvements in Rifle-Periscopes, of which the following is a specification.

This invention relates to an improved 10 rifle periscope, its object being to enable a soldier or other person to aline the sights along the barrel of his rifle from one side thereof by reflection at right angles, while he is protected by earthworks, sandbags, or 15 other suitable cover.

The invention consists essentially in attaching to the barrel of the rifle by means of a strap, clip, or other fastening, a small mirror arranged at an angle of 45° to the 20 usual line of sight, and substantially horizontal therewith.

But in order that the invention may be clearly comprehended, I now refer to the accompanying drawings, in which,

25 Figure 1 is a perspective view of my periscope attachment for sighting from the right, while

Fig. 2 is a similar view for sighting from the left side.

30 Fig. 3 is a partial elevation of a rifle showing the periscope attachment in position.

Fig. 4 is an elevation showing the method of using the attachment, while

35 Fig. 5 illustrates in perspective an attachment in which a double mirror is pivoted and may be changed from one side or the other according to the position taken up by the person aiming.

The same reference letters indicate the 40 same or corresponding parts.

A is a mirror preferably secured in a suitable casing B, having a semi-circular portion C capable of fitting over the barrel of a rifle in line with the sights and behind the 45 rear sight. D is a flexible strap for fastening the attachment in position on the barrel by means of the buttons, E, E. F is the barrel, and G is a portion of the stock. J is a sighting aperture in the casing which 50 is also open at its front K.

In using the periscope attachment the muzzle end of the rifle is rested on any convenient object, such as a sandbag, while the rifleman takes up a position at one side facing the mirror thereby enabling him to

aline the sights by reflection. At the same time he grasps the butt with one hand the thumb of his other hand being in contact with the trigger of the rifle as clearly shown in Fig. 4. 60

In Fig. 5, the mirror is a double one and with the casing B is made adjustable on the lower portion C around a pivot pin H or the like preferably situated between the two reflecting faces of the mirror so that the sights 65 of the rifle may be aligned from either side according as the facilities afforded by the cover require.

Having thus described my invention, what I claim as new and desire to protect by Letters Patent, is:—

1. A periscope attachment for rifles, comprising a casing portion; a supporting portion whereon said casing is rotatably mounted, adapted to detachably engage the barrel 75 of the rifle behind the rear sight; and a double mirror within said casing arranged in the line of the sights and at an angle of approximately 45° thereto; said mirror being moved by the rotation of said casing in one 80 direction or the other into position to enable the marksman to aline the sights from either side of the rifle by direct reflection.

2. A periscope attachment for rifles, comprising a casing rotatably mounted upon the 85 rifle barrel behind the rear sight; and a double mirror within said casing arranged in the line of the sights and at an angle of approximately 45° thereto; said mirror being moved by the rotation of said casing in one 90 direction or the other into position to enable the marksman to aline the sights from either side of the rifle by direct reflection.

3. A periscope attachment for rifles, comprising a box-like casing mounted upon the 95 barrel of the rifle behind the rear sight and having its front open; and a vertical double mirror within said casing arranged in the line of the sights and at an angle of approximately 45° thereto; said casing having 100 sight openings in its sides located opposite said mirror, said mirror being moved by the rotation of said casing in one direction or the other into position to enable the marksman to aline the sights from either side of 105 the rifle by reflection directly visible through the adjacent sight-opening.

In testimony whereof I have hereunto set my hand.

EBENEZER REGINALD MORRIS.
